UNITED STATES PATENT OFFICE.

WALTER E. FOSTER, OF CHICAGO, ILLINOIS.

AUTOMATIC BLOCK-SIGNAL SYSTEM.

1,011,602.

Specification of Letters Patent. Patented Dec. 12, 1911.

Application filed July 22, 1910. Serial No. 573,317.

To all whom it may concern:

Be it known that I, WALTER E. FOSTER, a citizen of the United States, and resident of Chicago, county of Cook, and State of Illinois, have invented certain new and useful 5 Improvements in Automatic Block-Signal Systems, of which the following is a specification, and which are illustrated in the accompanying drawings; forming a part thereof.

10 The invention relates to automatic signaling systems for railways, wherein the rails of the track are divided into a plurality of insulated lengths or sections, termed 15 "blocks," which extend between the signals and serve as conductors for a signal-controlling electric current.

The invention contemplates a novel combination of electric block signal apparatus 20 more particularly applicable to the operation of signals which normally give a "danger" or "stop" indication, the term normally being used in this connection and in the appended claims with reference to the 25 condition of the parts when no train is present in the block to which said parts immediately pertain, or in the neighboring blocks.

The object of the invention is to provide a 30 block signal system which shall be reliable in operation and in which a reduced number of line wire conductors will suffice for the operation of a remote signal, either by itself or in conjunction with a signal located at the end of the block immediately in front 35 of a train, and for the operation of the last mentioned signal to give so-called "distant" indications.

A detail of the invention contemplates the 40 use of relays of improved construction, whereby a main insulated track section or block may be subdivided into shorter sections having the rails of the track insulated from each other and relay apparatus employed for duplicating the electrical condition 45 established in the rails of one subdivision of a block in the rails of the remaining subdivision.

In the accompanying drawings—Figures 1, 2 and 3 are diagrammatic charts illustrating 50 four consecutive sections or blocks of railway track equipped with signaling apparatus arranged in accordance with the invention; Fig. 4 is similar to Fig. 2 and shows the use of the relay heretofore mentioned.

55 The rails of a track are shown in the drawings at 8 and 9. These rails are di-

vided, as at 7 (Figs. 1 and 2), into a plurality of insulated sections or blocks, four of which are completely shown. The several track sections or blocks, which are completely shown, are designated A, B, C and D, respectively. 60

For the purpose of disclosing the invention, the apparatus is illustrated as taking a form adapted to operate signals for indicating the condition of the track for traffic in one direction only, and a single signal, as a, b, c, d, is provided for each of the track sections or blocks A, B, C and D. An additional signal pertaining to a track section in advance of that designated D, is shown at e. Preferably each of the signals a, b, c, d and e is of a form adapted to give three indications. As shown, so-called three-position signals of well known construction 75 are employed. Each signal comprises an arm 17, pivotally mounted upon a standard 18. The arm 17 indicates the signal by its position, the signals a, b and e being shown in the "danger" or "stop" position, the signal c being shown in the "proceed" or "clear" position, and the signal d in the "caution" position. 80

Each of the signals, as a, b, c and d, is 85 preferably located adjacent that end of the corresponding track section or block A, B, C, D, at which a train moving in the prescribed direction will enter the block. The direction of traffic, as shown, is therefore 90 that indicated by the arrows designated 6.

The parts of the apparatus are illustrated 95 in the positions which they will occupy when a train is in the block designated B, after having passed through the block A. Such a train is diagrammatically represented in the drawings by the truck designated z. This truck forms an electrical short circuit or bridge between the rails 8, 9, of the track section or block which it occupies, as B.

A plurality of batteries, one for supplying 100 electric current to the rails 8, 9, of each of the track sections or blocks A, B, C and D, are represented in the drawings at 10^a, 10^b, 10^c, 10^d. These batteries are connected to the rails 8, 9, of the corresponding track 105 section or block adjacent that end of the block at which the rails will be first engaged by a train z moving along the track. An electro-magnet, having a polarized armature 12 and a plurality of neutral armatures 13, 110 14, 15 and 16, is also in circuit with the rails 8, 9, of each of the track sections or

blocks. Five such electro-magnets are illustrated in the drawings. These are designated 11, 11^a, 11^b, 11^c and 11^d, respectively. The electro-magnet 11 is in circuit with the 5 rails 8, 9, of a track section in rear of the section designated A, and the electro-magnets 11^a, 11^b, 11^c and 11^d, are in circuit with the rails of the track sections A, B, C and D, respectively. A similar electro-magnet 10 (not shown) will also be used in circuit with the rails 8, 9, of the track section E.

Each of the electro-magnets 11^a, 11^b, 11^c and 11^d is preferably connected to the rails of the corresponding track section at that 15 end remote from the battery, as 10^a, 10^b, 10^c and 10^d, supplying current to the rails of the same section. As shown, each of these connections is made by wires designated 23, 24.

20 The neutral armatures 13, 14, of each of the electro-magnets 11, 11^a, 11^b, 11^c, are movable between terminals 43, 45, and 46, 47, respectively, of the corresponding batteries, as 10^a, 10^b, 10^c and 10^d, and constitute a pole-changing switch for the circuit including 25 the rails 8, 9, of the next adjacent track section or block. By means of this arrangement, when the rails 8, 9, of one track section, as B, are electrically connected by the 30 wheels of a train, as z, whereby the current from the battery 10^b is shunted off from the electro-magnet 11^b, the current from the battery, as 10^c, supplying current to the rails of the next track section, as C, is reversed 35 in the rails 8, 9, of that section and in the coils of the corresponding electro-magnet, as 11^c.

The signals a, b, c, d and e, are operated 40 by electric current served from batteries, as 22^a, 22^b, 22^c, 22^d and 22^e, respectively. As shown, this battery current is supplied to a signal-actuating motor for moving the signal arm 17 to the "caution" and "clear" 45 positions, respectively, through separate circuits having a common return wire 25, the other wire of the circuit for moving the signal to the "caution" position being designated 26, and the corresponding wire of the circuit for moving the signal to the "clear" 50 position being designated 27. The signal-actuating motor is preferably housed within the signal standard 18. It may be of well known construction, and is not shown in the drawings. A second controlling circuit, including sections as A', B', C' and D', of line 55 wires X and Y, extending between the several signals, is also employed. If desired the same batteries 22^a, 22^b, 22^c, 22^d and 22^e, employed for serving the several signal 60 operating circuits just described, may also be employed for serving the controlling circuits, including sections of the line wires X and Y.

A controlling electro-magnet, as 19^a, 19^b, 65 19^c, 19^d, and 19^e, is located at each of the

signal stations. When three-position signals are employed, as shown, each of these electro-magnets has a polarized armature 20 and a neutral armature 21. A pole-changing switch, preferably operated by the movement of the signal arm 17, for changing the direction of current in an adjacent section of the line wires X and Y, is also employed at each signal station when signals adapted to give three indications are 70 used. As shown, each of these pole-changing switches includes a pair of movable blades, designated 28 and 29, respectively, and these blades are operatively connected to the movable arm 17 of the corresponding 75 signal by a pitman 30. The blades 28 and 29 co-operate with contacts, designated 31, 32 and 33. These blades engage the contacts 31, 32, respectively, when the signal arm 17 is in its normal or "danger" position, indicated at a, b and e, and are moved to engage the contacts 32, 33, respectively when the signal blade 17 is shifted to the "caution" 80 position indicated at d. Preferably the contacts 32, 33, are so disposed that the switch 85 blades 28, 29, remain engaged with them upon a further movement of the signal arm 17 to the "clear" position indicated at c.

The polarized armature 12 and the neutral armature 16 of each of the electro-magnets, as 11, 11^a, 11^b, 11^c and 11^d, co-operate with contacts designated 34 and 35, respectively. Both of these armatures serve as switches in the section of the line wire X which leads into a given signal station from 90 the next station in advance.

When the electro-magnet, as 11^a, is receiving current from the battery 10^a in the manner shown, the section B' of the line wire X is open, both by reason of the polarized armature 12 being held out of engagement with the contact 34, and by reason of the neutral armature 16 being held out of engagement with the contact 35. A reversal of current in the coils of the electro-magnet 11^a closes the next section of the line wire X by a movement of the polarized armature 12 of the electro-magnet into engagement with the contact 34. This position of the parts is shown at the electro-magnet 11^c, where the section D' of the line wire X is closed by the engagement of the polarized armature 12 of the electro-magnet 11^c with its contact 34. When the current from the battery, as 10^b, is shunted off from the coils of the electro-magnet by a bridging of the rails of the corresponding track section, as at z, the neutral armature 16 is released and closes the line wire X by engagement with the contact 35. This position of the parts is shown at 110 the electro-magnet 11^b.

The neutral armature 15 of each of the electro-magnets, as 11, 11^a, 11^b, 11^c, co-operates with a contact 36 and serves as a switch located in that part of the line wire X which 120

leads away from each signal station to the signal station located at the preceding track section or block. When the electro-magnet, as 11^a, is being served with current in either direction from the corresponding battery, as 10^a, the neutral armature 15 is held in engagement with the contact 36 and closes the section A' of the line wire X. When, however, the battery current is shunted off from the electro-magnet, as at 11^b, by the bridging of the rails 8, 9, of the corresponding track section B by the truck z, the armature 15 of the electro-magnet 11^b is released and becomes disengaged from the contact 36 to open the circuit in a section, as B', of the line wire X. The polarized armature 20 and neutral armature 21 of each of the electro-magnets 19^a, 19^b, 19^c and 19^d, serve as switches for directing current from the battery, as 22^a, 22^b, 22^c, 22^d and 22^e, into the circuit wires 25, 26 and 27 of the signal apparatus.

The polarized armature 20 coöperates with contacts designated 39 and 42, and the neutral armature 21 coöperates with contacts designated 38 and 40. Preferably the arrangement is such that when the signal arm 17 is to stand at the normal or "danger" position indicated at a, b and e, all of the three wires 25, 26 and 27, leading to its operating motor (not shown) are connected to the same pole, as 37, of a battery, as 22^a, 22^b, 22^c, 22^d and 22^e. The possibility of the signal arm being operated by a foreign current is thereby precluded. This position of the parts is shown by the armatures 20 and 21 of the electro-magnets 19^a and 19^e, where all of the wires 25, 26 and 27, leading to the signal a and e, respectively, are shown to be connected with the pole 37 of the battery 22^a or 22^e. Referring to Fig. 3 of the drawings, the wire 25 is directly connected to the pole 37 of the battery 22^e. The wire 26 is connected to this battery pole by being connected to the wire 25 by the engagement of the neutral armature 21 with the contact 38. The wire 27 is connected to the same battery pole by being connected to the wire 26 by the engagement of the polarized armature 20 with the contact 42, the wire 26 being in turn connected to the wire 25 in the manner just described.

When no train is in a given track section, as A and D, or in the section immediately in rear of it, current will be supplied to the electro-magnet, as 11^a, 11^d, from a battery, as 10^a, 10^d, through the rails 8, 9, in the proper direction to hold the polarized armature 12 out of engagement with the contact 34. Each set of neutral armatures, 13, 14, 15 and 16, are therefore normally raised, the armature 15 being in engagement with the contact 36 to close that section of the line wire X leading backwardly from a given signal station, as the one having the signal e,

and the armature 16 being out of engagement with the contact 35, whereby that section of the line wire X leading into a given signal station from the station next in advance is opened.

The presence of a train, as z, in any track section, as B, causes current to be supplied to the coils of the electro-magnet, as 19^c, 19^d, at each of two signals, as c and d, in advance of the train. Current is supplied to the coils of each of these electromagnets, as 19^c, 19^d, from the battery, as 22^d, 22^e, located at the signal station next in advance, as follows:—Current from the battery 10^b is shunted off from the electro-magnet 11^b by the bridging of the rails 8, 9, of the track section B by the train z. All of the neutral armatures, as 13, 14, 15, 16, of the electro-magnet 11^b, therefore fall. The neutral armature 16 of the electro-magnet 11^b, in falling, engages its contact 35, thereby electrically connecting the line wires X, Y, in the section C' through the coils of the electro-magnet 19^c, the connection from the line wire X to the line wire Y being by way of contact 35, neutral armature 16 of electro-magnet 11^b, coils of electro-magnet 19^c, and junction 44. If no train is in track section C, current from battery 22^d will now be supplied to the coils of the electro-magnet 19^c by way of the terminal 37 of the battery 22^d, wire 25 at signal d, switch blade 28 at signal d, contact 31 (the switch blades 28, 29, of signal d not having yet been moved from the position illustrated at signals a, b, c), junction 53, armature 15 of electro-magnet 11^c, and its contact 36 to section C' of line wire X, and returning by way of line wire Y in section C', to contact 32 at signal d, switch blade 29 at signal d, to terminal 41 of battery 22^d.

Current from the battery 22^e will be supplied to the coils of the electro-magnet 19^d, if no train be in either of the track sections C, D, as follows:—The neutral armatures 13, 14, of the electro-magnet 11^b, in falling, come into engagement with the terminals 45, 47, of the battery 10^e, whereby the current from this battery is reversed in the rails 8, 9, of the track section C, and in the coils of the electro-magnet 11^c. This throws the polarized armature 12 of the electro-magnet 11^c into engagement with its contact 34. If now no train is in the track section D, so that the neutral armature 15 of the electro-magnet 11^d is held in engagement with its contact 36 by current from the battery 10^d, current from the battery 22^e will be supplied to the coils of the electro-magnet 10^d by the following route:—Terminal 37 of battery 22^e, wire 25 at signal e, switch blade 28 at signal e, contact 31, junction 48, neutral armature 15 of electro-magnet 11^d, contact 36, section D' of line wire X, contact 34, at electro-magnet 11^c, polarized armature 12

of electro-magnet 11^c, junction 49, coils of electro-magnet 19^d, junction 50, section D' of line wire Y, junction 51, contact 32 at signal c, switch blade 29 at signal e, junction 52 to terminal 41 of battery 22^e.

The magnetization of each of the electro-magnets 19^c, 19^d, in the manner just described, throws the polarized armature 20 of these magnets out of engagement with their contacts 42 and raises the neutral armatures 21 of these magnets into engagement with their respective contacts 40. Current from the batteries 22^c and 22^d is thereby supplied to the actuating motors of the signals c and d, respectively. The signal operating circuit in each instance is the same, and that to signal c will be described as follows:—The terminal 37 of battery 22^c, wire 25 at signal c, junction 54, to signal, 20 wire 26 at signal c, neutral armature 21 of electro-magnet 19^c, its contact 40, to battery terminal 41 of battery 22^c. The blade of each of signals c and d, is thereby moved out of the "danger" or "stop" position by 25 the operation of the motor in any well known manner. If, as shown, three-position signals are employed, this movement of the signal will be in each case merely to the "caution" position. In making this movement, however, the switch blades 28, 29, connected with each signal arm 17 by the pitman 30, will be shifted from engagement with the corresponding contacts 31, 32, respectively, into engagement with contacts 35 32, 33, respectively, whereby the current from the battery 22^d will be reversed in the coils of the electro-magnet 19^c, causing a further movement of the signal c. That is to say, when the switch blade 28, associated 40 with the signal d, is in engagement with its terminal 32, the section C' of the line wire Y is connected to the terminal 37 of the battery 22^d, whereas the section C' of the line wire X was formerly connected with this 45 battery terminal by the engagement of the switch blade 28 at signal d with its contact 31. The section C' of the line wire X is now connected with the terminal 41 of battery 22^d through the armature 15 of the electro-magnet 11^c, the contact 33, and switch blade 50 29 at signal d.

The reversal of current in the coils of the electro-magnet 19^c, just described, causes the polarized armature 20 of that electro-magnet 19^c to be thrown into engagement with its terminal 42, and current from the battery 22^c is now supplied to the actuating motor of the signal c through the wires 25 and 27, whereas it was previously supplied by the wires 60 25 and 26. With the polarized armature 20 of the electro-magnet 19^c in engagement with the contact 42, current from the battery 22^c is supplied to the actuating motor of the signal c as follows:—Terminal 37 of battery 65 22^c, wire 25, junction 54 to signal c, wire 27,

polarized armature 20 of electro-magnet 19^c contact 42, junction 55, neutral armature 21 of electro-magnet 19^c, contact 40, to terminal 41 of battery 22^c. This causes a movement of the arm 17 of the signal c to the "clear" or "proceed" position illustrated in the drawings. As soon as the train z enters the track section C, and thereby cuts off current from the battery 10^c and the electro-magnet 11^c, current from the 75 battery 22^d will be cut off from the electro-magnet 19^c by the falling of the neutral armature 15 of the electro-magnet 11^c out of engagement with its contact 36, and the consequent opening of the section C' of line 80 wire circuit X and Y. The neutral armature 21 of the electro-magnet 19^c will then fall into engagement with its contact 38, whereby each of the wires 25, 26, 27, leading to signal c becomes connected to the same 85 terminal 37 of the battery 22^c as previously described, and current being thereby cut off from the actuating motor of the signal c, its signal arm 17 will fall to the "danger" or "stop" position.

Obviously, if a train had been in the track section C when the train z entered the track section B, the arm 17 of the signal c could not have been raised in the manner previously described, for the presence of a train 95 in the track section C would have shunted off the battery 10^c from the electro-magnet 11^c and opened the section C' of the line wire circuit X, Y, by the falling of the neutral armature 15 of the electro-magnet 11^c, 100 out of engagement with its contact 36, thereby preventing current from the battery 22^d being supplied to the electro-magnet 19^c. Similarly, if a train had been in the track section D when the train z entered the track 105 section B, the remote signal d would not have been raised to the "caution" position in the manner previously described, for current could not have been supplied to the electro-magnet 19^d from the battery 22^c, as the 110 section D' of the line wire circuit X, Y, would have been opened by the disengagement of the neutral armature 15 of the electro-magnet 11^d from its contact 36. If the remote signal d had not been raised to the 115 "caution" position there would, of course, have been no reversal of current in the coils of the electro-magnet 19^d by the shifting of the switch blades 28, 29, associated with the signal d and the near signal c would therefore have been moved only to the "caution" position, thus giving a "distant" indication of the presence of a train in the track section D.

In some instances it may be desirable to 125 use a relay, as between the ends of track sections that are of unusual length. In Fig. 4 of the drawings the track section C is shown as being subdivided into sub-sections S and T, by cutting the rails 8, 9, at 56, 57, 130

and a relay, generally designated by the numeral 58, is employed for duplicating the electrical condition established in the rails 8, 9, in sub-section S, in the parts of these 5 rails in sub-section T. The relay 58 comprises an electro-magnet 59. This electro-magnet is in circuit with the rails 8, 9 of sub-section S. It is therefore normally supplied with current from the battery 10^c.

10 The electro-magnet 59, as shown, has two polarized armatures, designated 60, 61, and two neutral armatures designated 62, 63. The neutral armature 63 is movable into and out of engagement with a contact designated 64, and forms a switch in the section C' of line wire X. When current from the battery 10^c is shunted off from the electro-magnet 59 of the relay 58, as by the presence of a train in subdivision S of the block 15 20 C, the neutral armature 63 falls out of engagement with the contact 64 to open the section C' of line wire circuit X, Y.

A battery, designated 65, is associated with the relay 58 for supplying current to the 25 electro-magnet 11^c in either direction. This battery has terminals, designated 66, 67, and 68, 69. The terminals 68 and 69 are connected to the same sides of the battery 65 as the terminals 67 and 66, respectively.

30 The polarized armatures 60, 61, of the electro-magnet 59, are insulated from each other, and each is connected to one of the rails 8, 9, of subdivision T of the track section C. The polarized armature 61 is connected to the rail 9 through wire 70, junction 71, and wire 35 72. The polarized armature 60 is normally connected to the rail 8 through wires 73. The polarized armatures 60 and 61 are movable between the battery terminals 66, 68, and 40 67, 69, respectively. They therefore constitute a pole-changing switch located between the battery 65 and the electro-magnet 11^c. This pole-changing switch is operated by the reversal of current in electro-magnet 59, 45 to produce a similar reversal of current in electro-magnet 11^c.

The neutral armature 62 constitutes a switch in the wires 73, which normally connects the polarized armature 60 to the rail 8. 50 A wire 76 leads from the contact 75 to the junction 71 between the wires 71 and 72. When current from the battery 10^c is shunted off from the electro-magnet 59 by the presence of a train in the sub-division S of 55 the track section C, the neutral armature 62 falls out of engagement with the contact 74 and into engagement with the contact 75, thereby opening the wire 73 leading from the polarized armature 61. If, therefore, the 60 current from the battery 10^c is reversed in the subdivision S of the track section C, that from the battery 65 will be reversed in the subdivision T of the track section C by the movement of the polarized armatures 60, 65 61, of the electro-magnet 59. If, on the

other hand, current from the batteries 10^c is shunted off from the electro-magnet 59, that from the battery 65 will be cut off from the electro-magnet 11^c by the falling of the neutral armature 62. At the same time the section C' of the line wire circuit X, Y will be opened by the falling of the neutral armature 63.

The arrangement of relay just described will not permit a false "clear" or "proceed" signal to be given, even if it should fail to operate by the adhesion of its polarized armatures 60 and 61 to the contacts which they engage. That is to say, if the polarized armatures 60, and 61 should adhere, as by fusion, to the terminals 68 and 69 respectively, thereby causing current from the battery 65 to be reversed in the rails 8, 9 of sub-division T, such reversal of current would only clear the signal d if track section D were unoccupied and if the signal d should be thereby cleared it would return to the "danger" or "stop" position immediately upon a train entering the track section D. On the other hand, if the polarized armatures 60, 61 should become adhered to the contacts 66 and 67 respectively, the only disarrangement of the operation of the system which would occur, would be that a reversal of current in sub-division S 95 of track section C would not effect a similar reversal of current in sub-division T, whereby signal d would not be moved to caution position and signal c would be moved only to caution position when a train occupied 100 track section B and track section C was unoccupied. For this reason the use of relays or so-called "cut sections" in the normal danger system of signals is rendered quite safe by means of the invention, for the greatest disarrangement of the system which can result from a failure of the polarized armatures of the relay to operate is that the system shall be temporarily transformed 105 into a normal clear system. It is therefore 110 unnecessary to use non-fusing contacts for the polarized armatures 60, 61 of the relay 58. Such contacts are characterized by high resistance. The arrangement described therefore has the further advantage 115 of permitting the use of low resistance metallic contacts.

I claim as my invention—

1. In a railway signal system, in combination, a track divided into a plurality of blocks, a pair of signals, said signals being located adjacent opposite ends of an intermediate block, a movable indicating arm for one of the signals, a controlling circuit for each of the signals, a closed track circuit including the rails of said intermediate block, a second track circuit including the rails of a different block, means operated by the bridging of the rails of the last-mentioned block for reversing the current 130

in the track circuit of the said intermediate block, a switch in the controlling circuit of the said signal having the movable indicating arm operated by the said reversal of current in the track circuit of the intermediate block, and a switch in the controlling circuit of the other signal operated by the said movable indicating arm.

2. In a railway signal system, in combination, a pair of closed track circuits, a current reverser in each of the track circuits, a signal controlling circuit and a pair of signal operating circuits, a switch in the signal-controlling circuit closed by the reversal of current in one of the track circuits, means for reversing the current in the signal controlling circuit controlled by the reversal of current in the other track circuit, neutral means operated by the signal-controlling circuit for closing one of the signal operating circuits, and polarized means operated by the signal-controlling circuit for closing the other signal operating circuit.

3. In a railway signal system, in combination, a track divided into a plurality of consecutive blocks, a separate closed track circuit including the rails of each block, a signal standing normally at danger and governing traffic through the blocks in a given direction, said signal being located adjacent that end of an intermediate block at which a train moving in the said given direction of traffic leaves the said intermediate block, a current reverser in the track circuit of the said intermediate block operated by the bridging of the rails of another block leading to the said intermediate block in the said given direction of traffic, means for clearing the signal controlled by the said reversal of current in the track circuit of the intermediate block, and means for preventing the operation of the signal clearing means controlled by the bridging of the rails of a block located beyond the signal in the said given direction of traffic.

4. In a railway signal system, in combination, a track divided into a plurality of blocks, a signal governing traffic through the blocks in a given direction, a normally open signal-controlling circuit, a closed track circuit including the rails of a block leading to the signal, a second track circuit including the rails of a block located beyond the signal, a normally closed switch in the signal-controlling circuit, a normally open switch in the signal-controlling circuit the closing of which closes the signal-controlling circuit when the first-named switch is closed, means for closing the second-named switch operated by a reversal of current in the first-mentioned track circuit, and means for opening the first-mentioned switch operated by the bridging of the rails of the second-mentioned block.

5. In a railway signal system, in combi-

nation, a track divided into a plurality of consecutive blocks, a separate closed track circuit including the rails of each block, a signal governing traffic through the blocks in a given direction, said signal being located adjacent that end of an intermediate block at which a train moving in the said given direction of traffic leaves the said intermediate block; a normally open signal-controlling circuit, a normally closed switch in the signal-controlling circuit, a normally open switch in the signal-controlling circuit the closing of which closes the signal-controlling circuit when the first-named switch is closed, a current reverser in the track circuit of the said intermediate block operated by the bridging of the rails of another block leading to the said intermediate block in the said given direction of traffic, means for closing the second-named switch operated by the reversal of current in the track circuit of the said intermediate block, and means for opening the first-mentioned switch operated by the bridging of the rails of a block located beyond the signal in said given direction of traffic.

6. In a railway signal system, in combination, a track divided into a plurality of consecutive blocks, a pair of signals governing traffic through the blocks in a given direction and each standing normally at danger, said signals being located adjacent opposite ends of an intermediate block, a separate closed track circuit including the rails of each block, a current reverser in the track circuit of the said intermediate block operated by the bridging of the rails of another block leading to the said intermediate block in the said given direction of traffic, means for clearing the signal located adjacent that end of said intermediate block at which a train moving in the said given direction of traffic enters said intermediate block controlled by the said bridging of the rails of the said block which leads to the said intermediate block, means for clearing the other said signal controlled by the said reversal of current in the track circuit of the intermediate block, and means for preventing the operation of each of the said signal clearing means controlled by the bridging of the rails of a block located beyond the corresponding signal in the said given direction of traffic.

7. In a railway signal system, in combination, a track divided into a plurality of consecutive blocks, a separate closed track circuit including the rails of each block, a pair of signals governing traffic through the blocks in a given direction, the said signals being located adjacent opposite ends of an intermediate block, a normally open controlling circuit for each of the signals, a current reverser in the track circuit of the

5. said intermediate block operated by the bridging of the rails of another block leading to the said intermediate block in the said given direction of traffic, a switch in the controlling circuit of the signal located adjacent that end of said intermediate block at which a train moving in the said given direction of traffic enters the said intermediate block closed by the said bridging of the 10 rails of the said block which leads to the said intermediate block, a switch in the controlling circuit of the other signal closed by the said reversal of current in the track circuit of the said intermediate block, and a 15 second switch in the controlling circuit of each of the signals opened by the bridging of the rails of a block located beyond the corresponding signal in the said given direction of traffic.
- 20 8. In a railway signal system, in combination, a track divided into a plurality of blocks, a pair of signals, said signals being located adjacent opposite ends of an intermediate block, a movable indicating arm for 25 one of the signals, a controlling circuit for each of the signals, a track circuit including the rails of said intermediate block, a second track circuit including the rails of a different block, means operated by the 30 bridging of the rails of the last-mentioned track circuit for changing the electrical condition in the track circuit of the said intermediate block, a switch in the controlling circuit of the said signal having the movable indicating arm operated by the said 35 change of electrical condition in the track circuit of the said intermediate block, and a switch in the controlling circuit of the other signal operated by the said movable 40 indicating arm.
9. In a railway signal system, in combination, a track divided into a plurality of blocks, a signal standing normally at danger and governing traffic through the blocks 45 in a given direction, a closed track circuit including the rails of a block leading to the signal in the said given direction of traffic, a second track circuit including the rails of a block located beyond the signal in the 50 said given direction of traffic, means for clearing the signal normally operable either upon a reversal of current in the track circuit of the said block leading to the signal or upon a bridging of the rails of the said 55 block leading to the signal, and means for preventing the operation of the signal clearing means controlled by a bridging of the rails of the said block located beyond the signal.
- 60 10. In a railway signal system, in combination, a track divided into a plurality of blocks, a signal governing traffic through the blocks in a given direction, a normally open signal-controlling circuit, a closed 65 track circuit including the rails of a block
- leading to the signal, a second track circuit including the rails of a block located beyond the signal, a normally closed switch in the signal-controlling circuit, a pair of normally open switches, the closing of either 70 one of which closes the signal-controlling circuit when the first-named switch is closed, one of said second-mentioned switches being closed by a reversal of current in the first-mentioned track circuit and the other 75 of said second-mentioned switches being closed by the bridging of the rails of the said block leading to the signal, and means for opening the first-named switch operated by the bridging of the rails of the said 80 block located beyond the signal.
11. In a railway signal system, in combination, a track divided into a plurality of blocks, a pair of signals, said signals being located adjacent opposite ends of an intermediate block, a movable indicating arm for one of the signals, a controlling circuit for each of the signals, a closed track circuit including the rails of said intermediate block, a second track circuit including the rails of a different block, means operated by the bridging of the rails of the last-mentioned track circuit for reversing the current in the track circuit of the said intermediate block, a switch in the controlling circuit of the said signal having the movable indicating arm operated by the said reversal of current in the track circuit of the intermediate block, a current reverser in the controlling circuit of the other signal operated by the said movable indicating arm, and means controlled by the said reversal of current in the controlling circuit of said other signal for changing said signal. 90
12. In a railway signal system, in combination, a signal adapted to give home and distant indications, a pair of normally open signal-operating circuits operating upon the said signal, for the said home and distant indications, respectively, a normally open signal-controlling circuit, means for closing the signal-controlling circuit, means for reversing the current in the signal-controlling circuit, neutral means operated by the signal-controlling circuit for closing one of said signal-operating circuits, and polarized means operated by the signal-controlling circuit for closing the other of said signal-operating circuits. 100
13. In a railway signal system, in combination, a track divided into a plurality of consecutive blocks, a signal adapted to give three indications, a closed track circuit including the rails of one of the blocks, a second track circuit including the rails of a different block, means operated by the bridging of the rails of the said second-mentioned block for reversing the current in the first-mentioned track circuit, a normally open signal-controlling circuit, means for closing 110

the signal-controlling circuit operated by the said bridging of the rails of the said second-mentioned block, signal-actuating means operable upon the said closing of the signal-controlling circuit, a current reverser in the signal-controlling circuit operated by the said reversal of current in the first-mentioned track circuit, and other signal-actuating means operable upon the reversal of current in the signal-controlling circuit.

14. In a railway signal system, in combination, a track divided into a plurality of consecutive blocks, a pair of signals governing traffic through the blocks in a given direction, one of said signals being located adjacent that end of an intermediate block at which a train moving in the said given direction of traffic enters said intermediate block, said signal being adapted to give three indications, and the other signal being located adjacent the other end of the same block, a movable indicating arm for the last-mentioned signal, a pair of closed track circuits, one including the rails of the said intermediate block and the other including the rails of another block leading to the said intermediate block in the said given direction of traffic, means operated by the bridging of the rails of the said other block which leads to the said intermediate block for reversing the current in the track circuit of the said intermediate block, a normally open controlling circuit for each of the said signals, means for closing the controlling circuit of the said first described signal operated by the said bridging of the rails of the said other block which leads to the said intermediate block, actuating means for the said first described signal operable upon the said closing of the controlling circuit of said signal, means for closing the controlling circuit of the said second described signal operated by the said reversal of current in the track circuit of the said intermediate block,

means for shifting the said movable indicating arm operable upon the said closing of the controlling circuit of the said second described signal, means for reversing the current in the controlling circuit of the said first described signal operated by the said shifting of the movable indicating arm, and other actuating means for the first described signal operated by the said reversal of current in the controlling circuit of said signal.

15. In a railway signal system, in combination, a track divided into a plurality of blocks, a separate closed track circuit including the rails of each block, a signal governing traffic through the blocks in a given direction, said signal being located adjacent that end of an intermediate block at which a train moving in the said given direction of traffic leaves said intermediate block, a current reverser in the track circuit of the said intermediate block operated by the bridging of the rails of another block leading to the said intermediate block in the said given direction of traffic, a signal controlling circuit, a normally closed switch in the signal-controlling circuit, a pair of normally open switches, the closing of either one of which closes the signal-controlling circuit when the first-named switch is closed, means for closing one of the said second-mentioned switches operated by the said reversal of current in the track circuit of the said intermediate block, means for closing the other of the said second-mentioned switches operated by the bridging of the rails of the said intermediate block, and means for opening the first-mentioned switch operated by the bridging of the rails of a block located beyond the signal in the said given direction of traffic.
